UNITED STATES PATENT OFFICE.

WILLIAM M. DUNCAN, OF ALTON, ILLINOIS.

MECHANICAL STOKER.

1,088,772.

Specification of Letters Patent. Patented Mar. 3, 1914.

Application filed April 8, 1912. Serial No. 689,214.

To all whom it may concern:

Be it known that I, WILLIAM M. DUNCAN, a citizen of the United States of America, and resident of Alton, in the county of Madison and State of Illinois, have invented certain new and useful Improvements in Mechanical Stokers, of which the following is a full, clear, and exact description, reference being had to the accompanying drawings, 10 forming a part of this specification.

My invention relates to mechanical stokers for furnaces and, more particularly stated, comprises adjustable means whereby the fuel resting upon the traveling grate at 15 the rear end of a mechanical stoker may be retained upon the grate for thorough consumption instead of being discharged over the tail end of the stoker before all of the combustible matter present therein has been 20 consumed.

Briefly stated, the improvement consists in an adjustable retardation device, preferably including a water back, located above the rear end of a stoker and serving to produce 25 a bank of ashes and other residue of combustion upon a traveling grate in such manner as to cause the fuel in front of the bank to be held on the grate until complete combustion has taken place. Permissible adjustment of the retardation device produces 30 a gap between the traveling grate and the retardation device through which the residue from the fuel is discharged over the tail of the grate whenever such discharge becomes 35 necessary or advisable.

Figure I is a view partly in elevation and partly in vertical longitudinal section of a portion of a furnace, the rear end of a stoker, and my retardation device. Fig. II is a 40 view partly in elevation and partly in vertical cross section of my retardation device and the supporting members in which said device is movable. Fig. III is an enlarged elevation of the retardation device as viewed 45 from one side of the furnace in which it is used.

In the drawings: A designates the side walls of a furnace, and B the frame of a stoker located in the combustion chamber of 50 the furnace, the stoker being provided with a traveling grate C of any usual construction.

My retardation device is located above the rear portion of the stoker C and is so mounted 55 as to normally occupy a position in which it is very slightly removed from the fuel and

residue carrying portion of the traveling grate C, and from which position it is removable away from the grate, preferably in a rearward direction, for the purpose of producing a gap between the retardation device and the grate that will allow residue from the fuel that has been restrained in front of the retardation device to be discharged over the tail end of the stoker. 60

The retardation device in its preferred form comprises a water back 1 that may be in the form of a tubular roller, as illustrated in the drawings, and which extends transversely across the stoker. Water is delivered to and discharged from the water back through conducting pipes 2 united to the former by couplings 3, which are designed to be rotated on the horizontal portions 2' of the conducting pipes 2. To provide for the 75 rearward and forward movement of the water back 1, said water back has secured to it hand wheels 4 furnished with handle arms 5 and including spur gears 6, which mesh with toothed racks 8, for the purpose of rolling 80 the water back from its normal position to an abnormal position.

7 designates housing boxes mounted in the furnace walls A, and in which the water back 1 may be adjusted by rolling it to and fro 85 for the purpose of producing or varying the gap between said water back and the stoker grate. These boxes serve as bearers for the racks 8 with which the spur gears 6 of the hand wheels 4 have engagement. The housing boxes 7 are preferably elongated in a horizontal direction and the racks 8 supported thereby are preferably arranged horizontally, or substantially parallel with the top surface of the stoker C. It will be apparent 90 that when the parts thus mentioned are arranged as stated, the water back may be rolled backwardly and forwardly in substantially a horizontal plane, thereby providing for the water back being normally positioned 100 directly over the portion of the traveling grate that supports the residue of fuel at the rear end of the stoker to a rear position that will produce a gap through which the residue may be discharged over the tail end of 105 the stoker.

It will be obvious that inasmuch as the water back 1 is adjustable to and fro within the elongated boxes 7, and is connected to the conducting pipe connections and means 110 for operating it exterior of the furnace, it is advisable to provide some means for pre-

venting the escape of air through said boxes from the combustion chamber in the furnace. The means I provide for this purpose are guard plates 9 fitted around the water back, 5 and extending through suitable guideways in the boxes 7 in which they slide when the water back is being adjusted.

It will be apparent that the desired rolling movement of the water back may be accomplished without interfering with the water back pipes by furnishing flexible connections between the said water pipes and the members they are attached to.

I claim:

15 1. The combination with a mechanical stoker having a traveling grate, of a rotatable barrier at the rear of said grate by

which the fuel resting upon the grate may be restrained while the grate is in motion, and means for rolling said barrier back and forth to vary the gap between the grate and the barrier.

2. The combination with a mechanical stoker having a traveling grate, of a cylindrical water back at the rear of said grate, 20 water conducting connections to which said water back is journaled, and means for rolling said water back back and forth to vary the gap between the grate and barrier.

WILLIAM M. DUNCAN.
